US0D1043630S

(12) **United States Design Patent** (10) **Patent No.:** **US D1,043,630 S**
(45) **Date of Patent:** **** Sep. 24, 2024**

(54) **HOUSING OF SIGNAL TRANSMISSION DEVICE**

(71) Applicant: **ACCTON TECHNOLOGY CORPORATION**, Hsinchu (TW)

(72) Inventor: **Chien-Hua Wu**, Miaoli County (TW)

(73) Assignee: **ACCTON TECHNOLOGY CORPORATION**, Hsinchu (TW)

(**) Term: **15 Years**

(21) Appl. No.: **29/843,797**

(22) Filed: **Jun. 23, 2022**

(30) **Foreign Application Priority Data**

Apr. 8, 2022 (CN) 202230193843.3

(57) **CLAIM**

The ornamental design for a housing of signal transmission device, as shown and described.

DESCRIPTION

FIG. 1 is a front perspective view of the housing of signal transmission device;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an enlarged partial view of a marked region 8 in FIG. 1;

FIG. 9 is an enlarged partial view of a marked region 9 in FIG. 1;

FIG. 10 is an enlarged partial view of a marked region 10 in FIG. 4; and,

FIG. 11 is an enlarged partial view of a marked region 11 in FIG. 5.

The broken lines are included for the purpose of illustrating the portions of the housing and form no part of the claimed design. The dot-dash broken lines indicate where the enlargements have been taken, and from no part of the claimed design.

1 Claim, 11 Drawing Sheets
